CONTROL DEVICE

Earnest J. Dillman, Detroit, Mich., assignor to
Detroit Lubricator Company, Detroit, Mich., a
corporation of Michigan

Application December 27, 1933, Serial No. 704,139

20 Claims. (Cl. 200—83)

My invention relates to new and useful improvements in control devices, and more particularly to a device including control means operable automatically in response to variation in the force exerted by a power means.

An object of my invention is to provide a control device having novel means for regulating the operation thereof in response to variation in the force exerted by the power means.

Another object is to provide a control device operable in accordance with the difference between two variable fluid pressures acting through opposed power means.

Another object is to provide novel means for regulating the differential operation of the control means.

Another object is to provide a control device of simple construction and which will be extremely sensitive and highly efficient in operation.

The invention consists in the improved construction and combination of parts, to be more fully described hereinafter and the novelty of which will be particularly pointed out and distinctly claimed.

In the accompanying drawings, to be taken as a part of this specification, I have fully and clearly illustrated a preferred embodiment of my invention, in which drawings—

Figure 1 is a top plan view of the control device embodying my invention;

Fig. 2 is a view in end elevation, looking from the right toward the left, facing Fig. 1;

Fig. 3 is a view in front elevation, with the front cover or closure member removed to show the internal construction;

Fig. 4 is a view in vertical central section on the line 4—4 of Fig. 1;

Fig. 5 is a view in horizontal section taken on the line 5—5 of Fig. 4, and

Fig. 6 is a detail view in section on the line 6—6 of Fig. 4.

Referring to the drawings by characters of reference, 1 designates generally a housing or casing which comprises a supporting member and which is preferably of electric insulating material, such as bakelite for example. The casing 1 has top and bottom walls 2, 3 which are joined by substantially vertical end walls 4, 5 and is closed at its back by a rear wall 6. A front cover or closure member 1, also of electric insulating material, engages the front edges of the side, top and bottom walls and is secured in position by a removable screw 8 which is screw-threaded into a substantially horizontal boss 9 projecting forwardly from the rear wall 6. Through the bot-

tom wall 3 there is an aperture 10 adjacent the end wall 5 and preferably provided with a marginal surrounding flange 11 which receives and has secured thereto a power means designated generally 12. The means 12 comprises a substantially cup-shaped container or casing 13 having a lateral, outwardly directed rim or flange 14 which seats against the casing flange 11 and which is tightly clamped and secured thereto by screws 15. Within the container 13 there is an annular member 16 having a circumferential flange 17 which fits tightly within the container 13 and seats on an upward facing shoulder formed in the container wall. The member 16 is preferably secured in position and hermetically sealed to the container wall by solder or the like, as at 18. Within the container 13 there is a substantially cylindrical, circumferentially corrugated, expandable-collapsible member or bellows element 19 which is of metal and is secured and hermetically sealed at its upper end to the inner periphery of the member 16, as at 20. The lower or inner end of the element 19 is provided with a head or end wall member 21, preferably of inverted cup-shaped form, having a marginal, outwardly directed rim or flange 22 which is secured and hermetically sealed to the lower or inner end of the element 19, as at 23. Rigidly secured to the head 21 and extending through a central aperture therein, there is a thrust member or plunger rod 24, one end of which extends downward through an aperture in the bottom wall of the container 13, and the other end of which extends upwardly into the casing through the aperture 10. The opening through the bottom wall of the container 13 is provided with a fitting 25 having a bore 26 extending longitudinally therethrough and opening at its upper end into the expandable chamber 27 formed between the element 19 and the container 13. The fitting 25 has an annular recess 25a in its inner end which surrounds the bore 26. A helical coil spring 25b surrounds the rod 24 and has one end seating in the recess 25a and its other end extending into and engaging the cup-shaped head 21. The spring 25b is held under compression between the head and the fitting and normally urges the rod 24 upward. The fitting bore 26 is preferably of reduced internal diameter, as at 27', to provide a downward facing annular shoulder co-operable with a stop member 28 rigid with the thrust member 24 to limit expansion of the chamber 27 and collapse of the element 19. The member 28 is preferably formed by the head of a screw or the like secured in and projecting from

the thrust member 24. Surrounding the member 24 there is a spring seat or abutment member 29 having a circumferential upstanding flange to prevent lateral displacement of the spring which seats on the member 29. The head 21 and the member 29 are preferably in engagement with each other and seat against a downward facing annular shoulder on the member 24, being held thereagainst by swaging a portion of the member 24 over on the head 21, as at 30. The thrust member 24 is preferably in two parts which are screw-threaded together with the upper part or portion 31 terminating adjacent the top wall 2. The spring seat member 28 receives one end of a range determining spring 32, preferably of the helical coil type, which surrounds the upper thrust member portion 31 and which is provided with a cap member 33 which seats on its upper end. The member 33 is preferably of substantially inverted cup-shaped form, having an aperture through its end wall for passage of the thrust member 24 and having oppositely directed lateral flange portions 34 projecting from the front and rear of the member 33 at its lower edge or rim. The portions 34 have upward facing, aligned V-grooves or bearing recesses 35 to receive a spring adjustment means, to be described. Through the end wall 5 substantially in the horizontal plane of the flange portions 34, there is an aperture 36 provided at its inner end with an insert 37, preferably of metal, through which an adjustment means 38 is adjustably screw-threaded. The means 38 preferably comprises a rotatable shaft having circumferential gear teeth 39 external of the wall 5 and having a longitudinal bore 40 opening through the end of the adjustment screw or means 38 into the interior of the casing 1. A bearing plug 41, preferably of hard metal such as chrome steel, is seated in the inner end of the bore 40 and is provided with an end recess to center one end of a thrust pin 42. Fulcrumed by or pivoted on a shaft 43 secured at its opposite ends in front and rear casing bosses 44, 45, there is an adjustment lever 46, preferably substantially U-shaped, with its base or cross member 47 provided with a bearing recess to receive the other end of the thrust pin 42 which provides a universal connection between the shaft 38 and the lever 46. The arms of the lever 46 extend toward the thrust member 24 and preferably terminate above the flange portions 34 such that the lever 46 straddles the cap member 33. The free ends of the arms of the lever 46 are provided with downward directed bearing points 47' which seat in the V-shaped grooves 35. The adjusting screw 38 is preferably provided with a knob or grip member 48 external of the casing 1. The gear teeth 39 are in mesh with the teeth of a dial plate 49 carried by and seating against the outside face of the end wall 5. The plate 49 which is circular is rotatably mounted on a stud 50 molded into the wall 5 and is secured on the stud 50 by a headed screw 51 threaded into the stud. The plate 49 is provided along its circumference with suitable indicia to indicate the range of operation of the control device, the indicia co-operating with a pointer or indicating finger 52 clamped to the outside face of the wall 5 by a screw 53 and overlying the plate 49. The upper end of the cap member 33 may be provided with a cover 54 of electric insulating material.

Secured to the inside face of the top wall 2 by screws 55 there is a supporting bracket member 56 which overlies the upper end of the thrust member 24 and which is provided with depending,

parallel, spaced, side members 57 which lie parallel to and are spaced from the front and rear walls of the casing 1. Positioned between the members 57 there is an operating lever 58 which is journaled adjacent one end for pivoted movement in a substantially vertical plane on a bearing shaft 59 secured in and extending between the side members 57. The lever 58 preferably has depending side flanges 60 jointed by longitudinally spaced cross members 61, 62. Intermediate the members 61, 62 the flanges 60 are provided with upwardly open recess portions 63, for a purpose to be described. Positioned between the horizontal portion of the bracket 56 and the lever cross member 61 there is a light spring 64 which is held under compression therebetween and which normally tends to rotate the lever 58 in a clockwise direction about its shaft or pivot pin 59 when facing Figs. 3 and 4. The spring 64 is positioned substantially at the end of the lever 58 adjacent wall 5 and seats at its lower end on an extension 65 projecting horizontally from the lever 58. The other end portion of the lever 58 which extends toward the end wall 4 is provided with a transverse portion 66 serving as an armature. Secured to the underface of the cross member 62 by a rivet or the like 67, there is a resilient contact carrying blade 68 which extends substantially to the free end of the lever adjacent wall 4 and terminates beneath the armature 66. The armature 66 is provided with a vertical aperture 69 to receive the reduced neck portion of a contact member 70 which is rigidly secured to the free end of the blade 68. The contact member 70 is cooperable with an adjustable contact member 71 which projects downward into the casing through the top wall 2 and which is adjustably screw-threaded in a sleeve member 72 secured in an aperture 73 in the top wall 2. The sleeve member 72, which is of metal, is secured to one end of a current conducting member 74 such as a copper strip which is sealed within and extends longitudinally through the walls of the casing 1. The metal strip 74 preferably leads longitudinally through the top wall 2 to the rear wall 6 and thence longitudinally downward through the same to a point adjacent the bottom wall 3 where it is connected to a binding post or terminal 75 positioned inside of or within the casing 1. The sealing of the strip or member 74 in the casing wall serves to conserve space, to prevent interference with the mechanism which might occur with an external lead wire, and to efficiently insulate the conductor from the parts of the mechanism. The armature 66 cooperates with a magnet 76, preferably of the U-shaped permanent type, which is carried by the end wall 4 adjacent and substantially parallel to the top wall 2 and which extends from wall 4 toward the end wall 5 with its poles or arms 77 positioned on opposite sides of the contact members 70, 71 and vertically between the top wall 2 and the lever 58. The magnet 76 is rigidly secured by a nut and bolt 78 or the like to the horizontal leaf of a hinge member 79 which has its other or vertical leaf rigidly secured to the inside face of the end wall 4 by screws or the like 80. The hinge member 79 is preferably of resilient sheet metal such that the inherent resilience of the member 79 urges the magnet 76 upward toward the top wall 2. The magnet 76 is adjustable relative to the contact members 70, 71 and the armature 66 by means of a screw 81 which is adjustably threaded in a sleeve member 82 fixed in an aperture through the top wall 2. The ad-

Justment screw 81 acts through a push rod 83 or electric insulating material having its opposite ends in engagement with the screw 81 and the head of the bolt 78, the resilience of the hinge 79 which acts through the magnet 76 serving to hold the rod 83 in position and the magnet in adjusted position. The screw 81 is operable by means of a knob or finger grip 84 having a depending, annular flange 85 which travels in an annular groove or recess 86 formed in the top face of the wall 2. The groove 86 is provided with an abutment 87 having oppositely directed faces cooperable with the oppositely directed faces on a depending stop finger 88 on the flange 85 to limit the rotation of the screw 81. The knob 84 is preferably provided with dial markings 84^a cooperable with a pointer 84^b preferably formed integral with the top wall 2 to indicate the position of the magnet 76.

20 Positioned between the lever flanges 63 and intermediate the lever cross members 61, 62, there is a lever member 89, preferably of electric insulating material, which lies substantially parallel to and in the plane of the lever 58. The lever member 89 is journaled for substantially vertical pivotal movement, parallel to the plane of movement of lever 58, on bearing pins or trunnions 90 which are secured in the bracket side members 57 and which project through the flange recesses 63 and above the flanges 60 into bearing sockets 91 formed in the side faces of the lever member 89. One end 92 of the lever member 89 extends into overlying, engageable relation with an abutment member 93, preferably a pin or rod rigid with the lever 58 and extending transversely between and secured at its opposite ends in the flanges 60. The abutment member 93 is preferably positioned between and substantially in the plane of the fulcrums for the lever 58 and the lever member 89.

40 The lever member 89 is provided with a vertical aperture 94 therethrough substantially centrally thereof which is preferably rectangular and receives the upper end portion of the thrust member 24. The thrust member is pivotally secured 45 in the aperture 94 by a pin 95 which extends horizontally through the lever member 89 and the upper end portion 31 of the thrust member, the aperture 94 being of sufficient cross-sectional area to permit rocking of the lever member on the end 50 of the thrust member. The lever 58 is electrically connected by a lead wire 96 to a metal insert 97 embedded and sealed within the rear wall 6, the insert being connected to a binding post 89 adjacent the binding post 75. The end wall 4 is preferably 55 provided with an aperture 99 for the passage of lead wires into the casing and which are to be connected to the binding posts 75 and 98.

The top wall 2 is provided with a mounting boss 100 which overlies the bracket 56. Rigidly secured 60 upon the boss 100 there is a power means designated generally 101, provided with a thrust member 102 which engages the upper end of the thrust member 24. The means 101 comprises a substantially inverted, cup-shaped container 103 having a lateral flange 104 which seats upon the boss 100 and is rigidly secured thereto by screws or the like 65 105. Within the container 103 there is a movable wall, preferably in the form of an expandable-collapsible, metal bellows 106 having a head 107 secured and hermetically sealed to one end of the bellows. The other end of the bellows 106 is secured and hermetically sealed to an annular member 108 provided with a circumferential flange which seats against a downward facing, annular 70 shoulder formed in the inside face of the side wall 75

of the container 103. The member 108 is preferably hermetically sealed to the container 103 by solder or the like, as at 109. The bellows head 107 is preferably substantially cup-shaped so that it extends into the bellows and is provided with a central aperture in which the thrust member 102 is rigidly secured and sealed. The thrust member 102 is preferably provided with a conical end portion which seats in a substantially conical recess formed in the top end of the thrust member 10 portion 31 to prevent lateral displacement of the engaged ends of the thrust members relative to each other and to permit angular movement of the thrust members relative to each other as the lever member 89 oscillates about its fulcrum. The end wall of the container 103 is provided with a fitting 110 having a longitudinally extending bore 111 therethrough which opens into the expandable chamber 112 formed within the container by the expandable wall. The fitting 110 is preferably 20 provided with a recess 113 surrounding the inner end of the bore 111. A helical coil spring 114 is seated at one end in the recess 113 and at its other end engages the head 107, being held under compression therebetween and surrounding the 25 thrust member 102. The force exerted by spring 114 is preferably substantially equal to the force of spring 25^b, each of the springs preferably being under a compression of fifteen pounds so that the thrust members will be held in engagement 30 with each other. The thrust member 102 is preferably provided with a stop positioned in the bore 111 and cooperable with an annular shoulder 116 in the bore 111. The stop 115 is preferably formed by the head of a screw or the like secured in the 35 end of the thrust member 102. The top wall 2 and the bracket 56 are provided with aligned apertures 117 for the passage of the thrust member 102 into the interior of the casing 1.

The operation of my control device will be described as employed in controlling the operation 40 of the burner of a heating apparatus wherein it is desired to maintain a predetermined difference of pressures between a certain pressure in the supply line and a relatively lower pressure in the 45 return line to the heating apparatus. However, the control device is not limited to this application which is merely illustrative of one of its uses as it is obvious that it may be employed in other apparatus wherein it is desired to control an operating means in response to a differential between 50 two pressures or two temperatures corresponding to the pressures. The terminal posts 75 and 98 will be connected to the control means for the burner of the heating apparatus by suitable lead 55 wires which enter the casing 1 through the opening 99. The fittings 25 and 110 will be connected by suitable pressure transmitting conduits to the supply and return lines respectively of the heating apparatus. Assuming first for illustration of operation 60 that the absolute fluid pressure in chamber 112 is constant, so that the force exerted by the wall 107 and through the thrust member 102 against movement of thrust member 24 by power means 12 is constant, then the force required to 65 be exerted by the power means 12 to break circuit at the contacts 70, 71 will be equal to the resisting force of spring 32 plus the resisting force of power means 101 acting through thrust member 102 and increased by the magnetic attraction of magnet 76 for armature 66 transmitted to thrust member 24 through lever 58 and lever member 89. When the pressure of the 70 fluid in the supply line and transmitted to the chamber 27 exerts through head 21 a force on 75

thrust member 24 equal to the algebraic sum of the opposing forces exerted by spring 32 and power means 101, the forces exerted by springs 114 and 25^b being equal and opposite, then the power means 12 will move thrust member 24 upward. As the member 24 moves upward, it will act through its connection 85 to turn lever member 88 clockwise of Fig. 4 about its pivot pins 90, bringing the lever end 92 into engagement with the abutment pin 93. Further movement of lever member 88 is now opposed by the attractive force of magnet 76 for armature 66 acting through lever 88, so that the force exerted by power means 12 must increase in order to break circuit. The initial movement of lever 88 by the increased force of power means 12 which will overcome the magnetic force will not however break contact due to the spring blade 68 which holds the contacts 70, 71 in engagement until the lever 88 is in motion, so that engagement between contacts 70, 71 will be broken quickly as the lost motion is taken up between blade 68 and the moving lever 88. Breaking of contact at 70, 71 will actuate the burner control means to stop the burner and the further increase of pressure in the supply line and the chamber 27. As the pressure in the chamber 27 decreases due to the stopping of the burner, the algebraic sum of the forces of the power means 102 and spring 32 acting on the thrust member 24 will move the same downward and rotate the lever member 88 counter-clockwise of Fig. 4 on its pivot pins 90. As the lever end 92 moves upward, the light coil spring 64, which only exerts sufficient force to lift the freely moving lever 58, will rock the lever 58 clockwise of Fig. 4 about its fulcrum 59, maintaining the abutment member 93 in engagement with lever end 92, until the armature 66 comes into the active field of the magnet 76 when the magnet poles 77 will attract the armature 66 and acting with the spring 32 will close the contacts 70, 71 with a quick movement. Further increase in the force tending to turn lever member 88 counter-clockwise of Fig. 4 will merely result in the lever end 92 moving away from and out of contact with the abutment member 93 so that the continued downward movement of the thrust member 24 will be unopposed by the lever 58. This provision for lost motion between the thrust member 24 and the lever 58 permits of the utilization of light weight moving parts which increases the efficiency of operation of the instrument. The annular downward facing shoulder on contact 70 cooperates with armature 66 to prevent engagement of the armature with the magnet poles and to maintain a slight air gap thereby enhancing the operation of the instrument. Closing of contacts 70, 71 establishes the following circuit through the instrument: from the terminal 75 through the lead member 74, contact members 71 and 70, blade 68, lever 58, lead wire 86 and connecting link 97 to the terminal 88, which places the burner in operation to again increase the pressure in the supply line and the chamber 27. From the foregoing, it will be apparent that the range of operation of the instrument, that is, the pressure at which contact will be made, the force of power means 101 remaining constant, is determined by the range adjusting spring 32. Rotation of the knob 48 will act through screw-threaded shaft 38, pin 42, lever 46 and cap member 33 to regulate the tension of spring 32 against the movable wall 21. As the force exerted by spring 32 is increased, the greater or higher the pressure will be in chamber 27

at which the contacts 70, 71 will be engaged. The differential operation of the instrument, that is, the pressure at which contact will be broken relative to the pressure at which contact is made, still assuming the force of power means 101 to be constant, is determined by the position, when the contacts are in engagement, of the magnet poles 77 relative to the armature 66. As shown, the instrument is set for its widest differential of operation, the magnet poles 77 being separated from the armature 66 by only a minute air gap. To decrease the differential between the pressures at which contact will be made and broken, the knob 48 is rotated to permit retraction of the member 83 so that the resilient force of the hinge member 79 can move the magnet upward thereby increasing the air gap between poles 77 and armature 66. The greater the air gap, the narrower or closer will be the differential of operation thereby requiring a less increase in the force of power means 12 after engagement between lever member 88 and lever 58 in order to overcome the attractive force of the magnet and break circuit between the contacts.

With the parts in the position shown, if the pressure in the return line and the chamber 112 should now increase, the thrust member 102 would force the thrust member 24 downward causing the lever end 92 to lift away from the lever abutment 93 resulting in lost motion, the contacts 70, 71 remaining in engagement. If, however, the pressure in chamber 112 decreased relative to the pressure in chamber 27 so as to exert a relatively less force on thrust member 24 through the thrust member 102, then when the amount of decrease became equal to the differential of operation determined by magnet 76, the force exerted by power means 12 would act through thrust member 24 to break contact as above described and stop the burner. If the pressure in the return line and the chamber 112 should now increase relative to the pressure in chamber 27, the contacts 70 and 71 being out of engagement and the circuit broken, then when the relatively increased force of power means 101 acting through thrust member 102 plus the force of spring 32 became equal to and overbalanced the force of power means 12 on thrust member 24, the thrust member 24 would move downward relieving the resistance to movement of lever 58 and permitting engagement of contacts 70, 71 under the force of spring 64.

It will be apparent from the foregoing description that I have provided an instrument in which the range of operation is determined by the force of spring 32, so that when the algebraic sum of the forces exerted by the opposed power means 12 and 101 becomes less than the force exerted by spring 32, the circuit will be made by engagement of contacts 70 and 71. The differential operation of the instrument as determined by the setting of magnet 76 will remain constant relative to the differential force determined by spring 32 and exerted by power means 12 and 101, so that breaking of circuit by disengagement of contacts 70 and 71 is at a constant increase of pressure for any given setting of the magnet 76. It will also be apparent that the operation of the instrument can be readily reversed by merely changing the position of the fulcrum pins 90 to the opposite side of the thrust member, i. e. the left side facing Fig. 4, so that upward movement of thrust member 24 will cause counter-clockwise rotation of lever member 88, facing Fig. 4. With the lever fulcrum so repositioned, the attractive

force of magnet 16 will oppose the spring 32 so that the algebraic sum of the forces exerted by power means 12 and 101 must be less in order to break circuit than the algebraic sum of the forces of power means 12 and 101 at which circuit will be made.

Although I have shown the control device as provided with fittings 25 and 110 for connection to sources of fluid pressure or to pressure conveying conduits, it will be apparent that the fittings may without invention be provided with bulb elements charged with a suitable expansible liquid such that the control device will operate by a differential between the pressures in the chambers 27 and 112 created by the temperatures to which the bulb elements are subjected.

What I claim and desire to secure by Letters Patent of the United States is:

1. A device of the character described, comprising a supporting casing, a lever fulcrumed at one end portion thereof in said casing and having side flanges with an aperture between said flanges, control means operable by said lever, a second lever fulcrumed in said casing and positioned in said aperture between said flanges, an abutment member carried by said first-named lever and positioned between said flanges intermediate the fulcrums for said levers, said abutment member being positioned beneath one end portion of said second-named lever for engagement thereby, power means carried by said casing, and a thrust member operatively connecting said power means to said second-named lever.

2. A device of the character described, comprising a supporting casing, a lever fulcrumed at one end portion thereof in said casing and having side flanges with an aperture between said flanges, control means operable by said lever, a second lever fulcrumed in said casing and positioned in said aperture between said flanges, an abutment member carried by said first-named lever intermediate the fulcrums for said levers and positioned between said flanges and beneath one end portion of said second-named lever for engagement thereby, power means carried by said casing, a thrust member operatively connecting said power means to said second-named lever, and a spring acting on said first-named lever and normally urging said abutment member toward said one end portion of said second-named lever.

3. A device of the character described, comprising a hollow supporting casing, a bracket member secured to the inside top wall of said casing and having depending side members, a lever positioned between said side members, said side members having bearing means pivotally supporting said lever, a contact member secured in and projecting inward from the top wall of said casing, a contact member resiliently carried by said lever and cooperable with said first-named contact member, a second lever pivotally supported by said side members and having its fulcrum spaced from the fulcrum of said first-named lever, an abutment member on said first-named lever engageable by said second-named lever and positioned intermediate said fulcrums whereby said second-named lever is operable to transmit motion to said first-named lever, power means, and a thrust member operatively connecting said power means and said second-named lever.

4. A device of the character described, comprising a hollow supporting casing, a bracket member secured to the inside top wall of said casing and having depending side members, a lever positioned between said side members, said side

members having bearing means pivotally supporting said lever, a contact member secured in and projecting inward from the top wall of said casing, a contact member resiliently carried by said lever and cooperable with said first-named contact member, a second lever pivotally supported in said casing and carried by said side members, an abutment member on said first-named lever engageable by said second-named lever whereby said second-named lever is operable to transmit motion to said first-named lever, power means, a thrust member operatively connecting said power means and said second-named lever, a range determining spring resisting operation of said thrust member by said power means, said first-named lever having an armature, a magnet having its poles positioned between said armature and the top wall of said casing and on opposite sides of said contact members, a resilient hinge member rigidly secured to the inside wall of said casing, means clamping said magnet to said hinge member, and adjustment means carried by said casing and cooperable with said magnet to regulate the position of said magnet relative to said armature whereby to adjust the differential operation of the device.

5. A device of the character described, comprising a supporting member, a lever pivotally carried by said supporting member, control means operable by said lever, an abutment member on said lever, a second lever pivotally carried by said supporting member and engageable with said abutment member, said abutment member being positioned between the fulcrums for said levers, said second-named lever having an aperture therethrough, power means carried by said supporting member, a thrust member having one end portion engaging said power means and having its other end portion extending into said aperture, and means in said aperture pivotally securing said second-named lever to said thrust member.

6. A device of the character described, comprising a supporting member, a lever pivotally carried by said supporting member, control means operable by said lever, an abutment member on said lever, a second lever pivotally carried by said supporting member and engageable with said abutment member, said abutment member being positioned between the fulcrums for said levers, said second-named lever having an aperture therethrough, power means carried by said supporting member, a thrust member having one end portion engaging said power means and having its other end portion extending into said aperture, means in said aperture pivotally connecting said second-named lever to said thrust member, a second power means carried by said supporting member, and a thrust member operable by said second-named power means and engaging said other end portion of said first-named thrust member whereby to oppose operation of said first-named thrust member by said first-named power means.

7. An electric switch comprising cooperable contact members, a lever for actuating one of said members, power means for moving said lever, a spring resisting said power means, a lever for regulating the resisting force of said spring, a manually operable adjusting screw, and a thrust pin having one end engaging said regulating lever and having its other end engaging said adjusting screw whereby said pin serves as a universal connection between said regulating lever and said screw.

8. An electric switch comprising cooperable contact members, a lever for actuating one of said members, power means, a thrust rod for transmitting movement from said power means to said lever, a helical coil spring surrounding said rod and resisting operation of said rod by said power means, an apertured cap member receiving said spring and surrounding said spring and said rod and acting to hold said spring under compression, 10 said cap member having oppositely positioned bearing means intermediate the ends of said spring, a spring regulating lever straddling said spring and engaging said bearing means, and means to actuate said regulating lever.
- 15 9. An electric switch comprising cooperable contact members, a lever for actuating one of said contact members, a thrust rod engaging said lever, opposed power means responsive to a fluid characteristic and engaging the ends of said rod, a 20 spring interposed between said power means and acting with one of said power means to oppose operation of the other of said power means, a regulating lever having a fulcrum support and cooperable with said spring, and an adjustment 25 screw acting through said regulating lever to hold said spring under compression.
10. A device of the character described, comprising a control means, a lever for actuating said control means, power means responsive to a fluid 30 characteristic for moving said lever, said lever having an armature, a magnet cooperable with said armature, resilient mounting means for said magnet acting to move said magnet relative to said armature, and an adjustable abutment member 35 opposing movement of said magnet by said mounting means and acting to hold said magnet against movement by said mounting means.
11. A device of the character described, comprising a supporting casing, a lever fulcrumed in 40 said casing and having an armature, control means operable by said lever, said lever having an opening intermediate its fulcrum and said armature, a second lever having a fulcrum and positioned in said opening and engageable with 45 said first-named lever between the fulcrums of said levers so that pivotal movement of said second-named lever in one direction pivots said first-named lever in the opposite direction, power means, a thrust member operable by said power 50 means and engaging said second-named lever, and a permanent magnet having a pole side face in substantially parallel and close proximity to said armature.
12. A device of the character described, comprising a supporting casing, a lever fulcrumed in 55 said casing and having an armature, control means operable by said lever, said lever having an opening intermediate its fulcrum and said armature, a second lever having a fulcrum and positioned in said opening and engageable with 60 said first-named lever between the fulcrums of said levers so that pivotal movement of said second-named lever in one direction pivots said first-named lever in the opposite direction, power 65 means, a thrust member operable by said power means and extending into said opening, means pivotally securing said thrust member to said second-named lever, and a magnet cooperable with said armature.
- 70 13. A device of the character described, comprising a supporting casing having a top wall, a lever fulcrumed in said casing and lying substantially parallel to and adjacent said wall, said lever having an armature adjacent one end, a 75 magnet in said casing and positioned substan-
- tially parallel to and between said wall and said armature, control means operable by said lever, means pivotally supporting said magnet, and adjustable means to move said magnet about its pivotal support relative to said armature. 5
14. A device of the character described, comprising a supporting casing having a wall with an aperture therethrough, a lever fulcrumed in said casing and lying substantially parallel to said wall, said lever having an armature adjacent one end, a magnet in said casing and positioned substantially parallel to and between said wall and said armature, control means operable by said lever, means carried by and projecting from a wall of said casing and pivotally supporting 15 said magnet, means cooperable with said first-named wall for pivotally moving said magnet relative to said armature, power means responsive to a fluid characteristic and mounted on said first-named wall external of said casing, and a thrust 20 member extending through said aperture and operable to transmit movement from said power means to said lever.
15. A device of the character described, comprising a supporting casing having a top wall, a lever fulcrumed in said casing substantially parallel to and adjacent said top wall, said lever having a contact member and an armature, a contact member carried by and projecting from said wall and cooperable with said first-named contact member, a magnet cooperable with said armature and positioned between said top wall and said armature, power means responsive to a fluid characteristic and supported externally by said casing, a thrust rod transverse to said lever and movable by said power means, said rod extending through an aperture into said casing, means operatively connecting said rod and said lever, a helical coil spring surrounding said rod and having one end abutting said rod, an abutment member 30 engaging the other end of said spring, a regulating lever engaging said abutment member and positioned substantially parallel to said first-named lever, an adjustment screw transverse to said rod and adjustably screw-threaded through 35 a wall of said casing, and a thrust pin interposed between said screw and said regulating lever and serving as a universal connecting means there- 40 between. 35
16. A device of the character described comprising a supporting member, a pair of levers pivotally carried by said supporting member, one of said levers having an abutment member for engaging the other of said levers, said abutment member being disposed between the fulcrums of said levers whereby pivotal movement of one of said levers in one direction pivots the other of said levers in the opposite direction, a control means operable by said levers, a power means carried by said supporting member, and a thrust member operable by said power means for transmitting movement to said levers to 50 actuate said control device. 55
17. In a control device, a supporting member, a pivotal switch arm carried by said supporting member and having an abutment member, a pivotal lever carried by said supporting member and arranged to engage said abutment member when pivoted in one direction to move said switch arm to open circuit position, said abutment member 60 being located between the pivot points of said switch arm and said lever so that said switch arm will be pivoted by said lever in an opposite direction thereto, a power means, a thrust rod operable by said power means and having pivotal con- 70 75

nection with said pivotal lever, a second power means operable to move said thrust rod and oppose said first-named power means, said pivotal lever being pivoted upon movement of said thrust rod by said second-named power means without transmitting such movement to said switch arm, and spring means operable to move said switch arm toward closed circuit position upon a pre-determined movement of said thrust member by 10 said second-named power means.

18. A device of the character described, comprising a supporting structure, a lever pivotally supported by said structure and having an armature, control means operable by said lever, a 15 leaf spring secured at one end to said structure, a magnet carried by said spring and cooperable with said armature, and means to flex said spring to adjust the position of said magnet relative to said armature.

20. 19. A device of the character described, comprising a casing having a top wall and a bottom wall, a power means carried by said bottom wall, a thrust member operable by said power means and extending toward said top wall, a substantially straight lever pivotally supported adjacent one end wall of said casing and extending transverse to said thrust member toward the opposite end wall of said casing, means operatively con-

necting said thrust member and said lever, control means carried by the free end of said lever, said lever lying substantially parallel to and being movable toward and from said top wall, the free end portion of said lever defining an armature, a magnet extending from adjacent said opposite end wall toward said lever and having one end positioned between said armature and said top wall, means under tension supporting said magnet and urging said magnet in one direction 10 relative to said armature, and means cooperable with said tensioned supporting means for adjusting and opposing movement of said magnet relative to said armature.

20. A control device comprising a supporting 15 means, a lever pivotally supported by said supporting means, said lever having an aperture therethrough, control means operable by said lever, a second lever, said second-named lever being positioned in the aperture of said first- 20 named lever and being arranged to pivot in one direction to pivot said first-named lever in the opposite direction, said second-named lever being arranged to pivot in another direction without transmission of movement to said first-named lever, and means for pivoting said second-named lever. 25
